UNITED STATES PATENT OFFICE.

ANDREW BUCHANAN, OF JERSEY CITY, NEW JERSEY.

IMPROVEMENT IN VALVES FOR STEAM-ENGINES.

Specification forming part of Letters Patent No. 36,556, dated September 30, 1862; antedated
March 30, 1862.

To all whom it may concern:

Be it known that I, ANDREW BUCHANAN, of Jersey City, in the county of Hudson and State of New Jersey, have invented certain Improvements for the Relief of the Faces and Seats of the Slide-Valves of Steam-Engines from Unnecessary Pressure; and I do hereby declare that the following is a full, clear, and exact description of the same, reference being had to the accompanying drawings, forming part of this specification, in which—

Figure 1 is a plan view of the valve-chest of a steam-engine with the cover removed to expose to view the valve and its appurtenances. Fig. 2 is a longitudinal section taken through the chest in the plane indicated by the line x x in Fig. 1. Fig. 3 is a longitudinal section taken centrally through the valve-chest and valve. Fig. 4 is a transverse section taken through the chest in the plane indicated by the line y y in Figs. 1 and 3. Fig. 5 is a top view of the valve.

Similar letters of reference indicate corresponding parts in the several figures.

This invention relates to transferring a desirable portion of the pressure produced by the steam on the back of the valve to a series of rollers arranged to run upon tracks within the valve-chest.

It consists in a certain construction and arrangement of and means of adjusting the tracks upon which such rollers run; also, in certain means of combining the rollers with the valve and adjusting them relatively thereto.

To enable others skilled in the art to make and use my invention, I will proceed to describe its construction and operation.

A is the valve-chest.

$a a$ is the valve-seat, in which the steam-ports $b b$ and exhaust-port c are arranged in the manner common to engines which have but one valve for induction and exhalation.

d is the inlet-port by which steam enters the valve-chest from the boiler.

C is the valve, which may be of the common construction, but which is represented with its sides and ends corrugated, as shown at $e e$, to make them flexible and elastic, and which has a lip, n , at each corner to give it a greater length of bearing on the seat, for the prevention of its rocking, without interfering with the arrangement of the ports.

D is the yoke, applied to the valve in the usual manner, and E is the stem.

F F are the rollers, which partly support the valve, two or more on each side of the valve, and G G are the ways on which the rollers run. The ways G G consist of two flat bars of steel supported at their ends by screws $e e$, which screw through tapped holes in the said bars and rest on bearings $f f$ provided for them in the corners of the valve-chest, each bar being fitted with two of said screws, one near each end, and the bearing-points of the screws being rounded or otherwise so formed as to allow the bars G G to rock laterally in some degree, for the purpose of adapting themselves to the peripheries of the rollers F F. By turning these screws in the tapped holes in the bars the latter may be separately leveled lengthwise, and so adjusted relatively to each other and to the valve-seat that the rollers running upon them (the face of the valve being properly adjusted to the rollers, as will be presently described) will keep the valve parallel with its seat both longitudinally and laterally, and so support it that it will not press upon the seat sufficiently to produce any wear either of its own face or of the seat, and yet will work steam-tight. The bars G G are further supported at the middle of their length each by one of the two screws $g g$, which pass freely through fixed lugs $h h$ on the interiors of the sides of the valve-chest, the heads of the said screws resting upon the tops of the said lugs; but these screws $g g$ might be dispensed with by making the bars G G of sufficient thickness to give them the necessary stiffness.

The rollers F F are arranged in pairs on axles H H, square portions of which are fitted into recesses $i i$, of corresponding form, in the lower sides of the two bars I I, which are bolted by screw-bolts $l l$, or otherwise firmly secured on the top of the valve, close to the sides thereof, and which project over the ends of the valve for the reception of the axle; and these bars have tapped holes at the backs of the recesses $i i$ for the reception of set-screws $j j$, which serve to adjust the valve relatively to the rollers so that its face will be parallel with the ways G G, and consequently parallel with the valve-seat as the rollers run upon the said ways, and the mode of combining the axles with the valve by the recesses i .

i in the bars *I I* allows the valve to be lifted from its seat in case of an accumulation of water in the cylinder or of great pressure occurring on the exhaust side of the piston in case of very sudden reversal of the engine with the cylinder full of steam. Sectors may be employed instead of rollers of complete circular form.

The valve and its appurtenances are adjusted before the cover *L* of the valve-chest is put on. When the valve is made with elastic sides, as shown at *e e* in Fig. 3, the ways *G G* are so adjusted relatively to the valve-seat by the screws *e e g* and the valve so adjusted to the rollers *F F* by means of the screws *j j* that the valve supported by the rollers running on the ways will allow every portion of the face of the valve to bear in some degree and uniformly on the seat, and when this has been done the screws *e e* are all turned down a uniform distance to raise the face of the valve from the seat. When the pressure of the steam comes on the so-adjusted valve, it presses it down into contact with the seat, but yet does not press it so hard thereon as to produce great friction or wear. When the valve is of the usual kind, the adjustment by the screws is intended to be such that the face will just touch the seat and work steam-tight thereon, but will work with very little friction.

The flexible elastic-sided valve does not re-

quire so extremely delicate an adjustment as that which is entirely rigid. By making the valve with a flexible and elastic back the same result may be obtained as by its construction with flexible and elastic sides.

The advantages obtained by this invention over other modes of applying the rollers and their appendages consist, principally, in the facility afforded for extreme accuracy of adjustment of the valve.

I do not claim, broadly, transferring a portion of the pressure of the steam on the back of the valve to a series of rollers; but

What I claim as my invention, and desire to secure by Letters Patent, is—

1. The employment as ways for the valve-rollers to run upon of bars adjustable by screws, substantially as herein specified.

2. Combining the roller-axes with the valve by means of recesses *i i* in the bars *I I*, or their equivalents, attached rigidly to and projecting over the ends of the valve, substantially as and for the purpose herein specified.

3. The set-screws *j j*, applied in combination with the bars *I I*, or their equivalents, and the roller axles, substantially as and for the purpose herein specified.

ANDREW BUCHANAN.
